Primary Examiner — Susan Bennett Hattan*Assistant Examiner* — Elizabeth Sun Ko(74) *Attorney, Agent, or Firm* — Lucian Wayne Beavers;
 Alex H. Huffstutter; Patterson Intellectual Property Law,
 PC(57) **CLAIM**

What is claimed is the ornamental design for a shelf divider clip, as shown and described.

DESCRIPTION

FIG. 1 is a front perspective view showing the shelf divider clip of Applicants' invention.

FIG. 2 is a rear perspective view of the shelf divider clip of FIG. 1.

FIG. 3 is a front elevation of the shelf divider clip of FIG. 1.

FIG. 4 is a right side elevation of the shelf divider clip of FIG. 1, the left side elevation view being an identical mirror image thereto.

FIG. 5 is a rear elevation of the shelf divider clip of FIG. 1.

FIG. 6 is a top plan view of the shelf divider clip of FIG. 1;

and,

FIG. 7 is a bottom plan view of the shelf divider clip of FIG. 1.

The broken lines in the drawings illustrate portions of the shelf divider clip which form no part of the claimed design.
